(57) **CLAIM**

The ornamental design for a cookware handle as shown and described.

DESCRIPTION

FIG. 1 is a top perspective view of the cookware handle showing my new design;

FIG. 2 is a side view thereof;

FIG. 3 is another side view thereof;

FIG. 4 is a back view thereof;

FIG. 5 is a front view thereof;

FIG. 6 is a top view thereof;

FIG. 7 is a bottom view thereof;

FIG. 8 is a top perspective view thereof in a folder configuration.

FIG. 9 is a top perspective view thereof in a second environment of use;

FIG. 10 is a side view thereof in a second environment of use;

FIG. 11 is another side view thereof in a second environment of use;

FIG. 12 is a back view thereof in a second environment of use;

FIG. 13 is a front view thereof in a second environment of use;

FIG. 14 is a top view thereof in a second environment of use;

FIG. 15 is a bottom view thereof in a second environment of use;

FIG. 16 is a top perspective view thereof in a second environment of use in a folder configuration;

FIG. 17 is a top perspective view thereof in a third environment of use;

FIG. 18 is a side view thereof in a third environment of use;

FIG. 19 is another side view thereof in a third environment of use;

FIG. 20 is a back view thereof in a third environment of use;

FIG. 21 is a front view thereof in a third environment of use;

FIG. 22 is a top view thereof in a third environment of use;

FIG. 23 is a bottom view thereof in a third environment of use;

FIG. 24 is a top perspective view thereof in a third environment of use in a folder configuration;

(Continued)

FIG. 25 is a top perspective view thereof in a fourth environment of use;

FIG. 26 is a side view thereof in a fourth environment of use;
FIG. 27 is another side view thereof in a fourth environment of use;

FIG. 28 is a back view thereof in a fourth environment of use;

FIG. 29 is a front view thereof in a fourth environment of use;

FIG. 30 is a top view thereof in a fourth environment of use;
FIG. 31 is a bottom view thereof in a fourth environment of use; and,

FIG. 32 is a top perspective view thereof in a fourth environment of use in a folder configuration.

The broken lines in the drawings illustrate portions the cookware handle which form no part of the claimed design.
